ABSTRACT

In the hydrodesulfurization of bitumen from certain natural tar sands, such as the Athabasca sands, acceptable hydroconversion levels can be obtained by the use of particulate contact solids operating in an up-flow liquid phase ebullated bed system at a conversion rate such that a maximum heptane-insoluble number of 40 is not exceeded. The parameters of operation depend to some extent on the solids in the bitumen.

HYDROGENATION OF RESIDUUM

BACKGROUND OF THE INVENTION

The ebullated bed system described by Johanson in U.S. Reissue Pat., No. 25,770, has proved successful in hydrogenation of petroleum residuum, including hydrocracking and hydrodesulfurization of a wide variety of stocks. The advantages of high throughput, uniform temperature, low pressure drop and non-plugging characteristics have been of great benefit to residuum processes. Liquid phase conditions assure good catalyst contact with no substantial attrition, and with the internal recirculation the catalyst bed has an average age which can be easily changed, without stopping the operation, by the mere addition or withdrawal of catalyst.

In processing the bitumen from natural tar sands, such as Athabasca sands which contain a substantial amount of asphaltenes and inert solids including sand, it was observed that during apparently "satisfactory" operations a tarry, sticky material was continuously formed over a period of a few days on stream at a conversion in excess of 50 percent of the material boiling over 975°F. Lower conversion rates become economically unsatisfactory.

SUMMARY OF THE INVENTION

The hydroconversion of a bitumen derived from natural tar sand having at least 50 weight percent boiling above 975°F such as Athabasca tar sands and similar tar sands materials containing substantial amounts of asphaltenes and inerts can be accomplished on a continuous high level basis in an ebullated bed system by limiting conversion to not exceed the production of a product having a critical heptane insoluble number. This can be accomplished by variations in operating conditions such as lower temperatures, higher pressures and maintaining a limited solids addition and removal rate such that this heptane insoluble number is not reached.

DESCRIPTION OF THE DRAWING

The FIGURE is a schematic view of an ebullated bed reactor.

PREFERRED FORM OF EMBODIMENT

As more specifically shown in the drawing, an asphaltene and inert sand containing bitumen feed 10 and hydrogen from line 12 are fed by line 14 upflow through a reactor generally designated 18. This reactor is typical of that shown in U.S. Reissue Pat., No. 25,770. The reactor has a liquid distributor and contact solids support 20 so that the liquid and gas passing upwardly through the reactor 18 will tend to put the solids in random motion in the liquid.

The contact particle size range is usually a narrow size range usually between 3 and 325 mesh (U.S. Std.) or sand having a size of less than 10 microns for uniform expansion under controlled liquid and gas flow conditions. An upflow liquid velocity between 1 and 100 gallons per minute per square foot of reactor cross section will maintain the bed of solid particles ebullated without substantial carryover of the solids. The solids may be the residual tar sand themselves or a catalyst but I find that the bitumen heretofore treated having high levels of sand concentration was most effective. If the bitumen was low in sand, recycle would concentrate the sand to be most effective as described in my

U.S. Pat. No. 3,151,054. The liquid flow rate, the density of the solids and the lifting effect of the hydrogen are factors in the buoyancy of the solids.

By control of the solids particle size and density and liquid and gas velocities and taking into account the viscosity of the liquid under the operating conditions, the solids bed may be expanded to have a definite level or interface in the liquid as indicated at 22. The settled level of the solids would be considerably lower than level 22. Normally bed expansion should be at least 10% and seldom over 100% of the static level.

In a reactor system of this type, a vapor space 23 is provided above the liquid level 56 from which a vapor overhead completely free of liquid, is removed at 24. The gaseous portion which is largely hydrogen, may be recovered by conventional means and after being reheated can be recycled to the feed line 14 to the reactor.

A heavy liquid, substantially free of solids, is separated from the effluent in the upper part of reactor 18 by trap tray 43 and drawn off at 44.

If a catalyst is used, it can be a typical hydrogenation catalyst from the group of cobalt, molybdenum, nickel and tungsten and mixtures thereof carried by a support from the group of silica, alumina and mixtures thereof.

Circulation of liquid from above the solids interface 22 to below the distributor deck 20 may be desirable to assure completeness of the reaction and to establish a sufficient upflow liquid velocity to assist in maintaining the solids in random motion in the liquid. As described in the Johanson U.S. Reissue Pat., No. 25,770, recycle can be established by an external pump on heavy liquid line 44 with a connection back to feed line 14.

Operability of the ebullated bed system to assure contact and uniform (iso-thermal) temperature depends on the random motion of the relatively small solids in the liquid environment resulting from the buoyant effect of the upflowing liquid and gas. With a non-uniform distribution of liquid flow, upsets take place, usually resulting in coke deposits.

Different tar sand feedstocks are found to have more or less asphaltene coke pre-cursors which tend to aggravate the operability of the pumps and recycle piping due to the plating out of tarry deposits. While these can be washed off by lighter diluent materials, the unit may become completely coked up and require premature shut down.

I have found that I can anticipate such condition by the use of a test procedure which I designate as the heptane insoluble number (HIN). Such test, an adaptation of ASTM (American Society for Testing Materials) test D 1796 is as follows:

50 cc of reactor liquid are mixed with an equal volume of heptane, heated to 120°F and centrifuged for 20 minutes. The material thrown out of solution, expressed as a percentage of the oil is designated the HIN (heptane insoluble number).

As described hereinafter, certain tests were made on the products from bitumen of the following type:

INSPECTION ON ATHABASCA TAR SANDS BITUMEN

	"A"	"B"	"C"
Gravity, °API	8.9	5.5	8.5

-Continued

INSPECTION ON ATHABASCA TAR SANDS BITUMEN

	"A"	"B"	"C"
Sulfur, Wt. %	4.88	4.85	4.92
Ash, Wt. %	0.79	3.22	0.72
Carbon, Wt. %	82.8	81.2	83.50
Hydrogen, Wt. %	10.51	10.15	10.73
Nitrogen, ppm	3900	4081	—
Metals, ppm	455	493	—

A number of runs were made varying the factors of solids and catalyst, space velocity, hydrogen throughput, temperature and pressure.

The following examples give the operating details:

EXAMPLES

	I	II	III	IV	V	VI
Stock No.	3332	3241	L-329	L-330	L-324	L-331
Run	185-169	185-148	201-53	201-54	185-167	201-55
% Ash in Reactor	—	32.1	3.9	18.9	48.8	30.0
Temperature	820°F	820	820	820	820	820
Pressure, psig	750	750	750	750	750	750
Space Velocity V _f /hr/V _r	1.5	1.5	1.5	1.5	1.5	1.5
Gravity °API	9.6	3.2	7.1	6.4	—	5.1
S Wt. %	4.68	4.94	5.34	5.01	—	5.02
Ash, Wt. %	0.62	4.02	0.47	1.83	—	3.04
Carbon, Wt. %	83.5	80.6	—	—	—	—
H ₂ , Wt. %	10.55	10.04	—	—	—	—
BS&W, Wt. %	1.5	6.8	1%	3%	—	5.6
HIN	32	26	48	38	40	30
Results	Plugged Satis.	Plugged Outline	Coked Satis.	Plugged	—	—
			Restricted			

While specific examples are set forth above, I find the following parameters for hydroconversion of tar sand bitumen to be generally applicable:

	Range	Preferable
Space Vel. V _f /hr/V _r	0.5 - 2.0	0.8 - 1.5
Pressure, psig	750 - 2000	1200 max.
Temperature, °F	750 - 850	about 825

I also have observed that for conversions above 70% the bitumen stocks having a low solids content required a low maximum heptane insoluble number whereas bitumen stocks having higher solids content would operate successfully with higher heptane insoluble numbers.

From the foregoing examples it can be determined that a heptane insoluble number of more than 40 should not normally be reached and for certain stocks, it may be necessary to restrict the operating conditions so that the number is not more than 32.

While a preferred form of embodiment of the invention has been shown and described, I am aware that modifications may be made thereto within the scope and spirit of the disclosure herein and of the claims appended hereinafter.

I claim:

1. A process for enhancing the operability of an ebullated bed system for the hydroconversion of a residuum bitumen feedstock derived from natural tar sands and having at least 50 weight percent of hydrocarbons boiling above 975°F and composed substantially of asphaltenes, wherein the feedstock and hydrogen pass upwardly through a reaction zone containing particulate contact material having a close size range in the range of 3 to 325 mesh (U.S. Std.) under conditions to place

the contact particles in random motion in the liquid, and hydroconversion conditions are maintained in the reaction zone in a temperature range between about 750° and 850°F, and total pressures are in the range of 750-2,000 psig, and with a space velocity in the range of 0.5 to 2.0 V_f/hr/V_r, the improvement which comprises maintaining reaction conditions such that the liquid effluent from the reaction zone has a heptane insoluble number under 40.

2. A process as claimed in claim 1 wherein the feedstock is a bitumen recovered from Athabasca tar sands, and the heptene insoluble number is kept below 32.

3. A process as claimed in claim 1 wherein the conversion of materials boiling above 975°F to materials boiling below 975°F is above 50%.

4. A process as claimed in claim 1 wherein the bitumen contains in the order of less than 1% of ash and the operating pressure is in the order of 750 psi hydrogen partial pressure, the temperature is in the order of 820°F, the space velocity is about 1.5 V_f/hr/V_r, and the conversion of 975°F plus material is over 60 percent.
